UNITED STATES PATENT OFFICE.

CHARLES N. ALDERMAN, OF STREATOR, ILLINOIS.

CAR-COUPING.

SPECIFICATION forming part of Letters Patent No. 443,841, dated December 30, 1890.

Application filed October 2, 1890. Serial No. 366,836. (No model.)

To all whom it may concern:

Be it known that I, CHARLES N. ALDERMAN, a citizen of the United States of America, residing at Streator, in the county of La Salle 5 and State of Illinois, have invented certain new and useful Improvements in Car-Couplings; and I do hereby declare the following to be a full, clear, and exact description of the invention, such as will enable others skilled in 10 the art to which it appertains to make and use the same, reference being had to the accompanying drawings, and to letters of reference marked thereon, which form a part of this specification.

15 This invention relates to improvements in car-couplings, the same being designed more particularly as an improvement upon my prior patent, dated December 16, 1884, No. 309,329, the present invention consisting in 20 certain details of construction, whereby the draw-head can be readily converted from an automatic coupling into one using the usual coupling pin and link.

In the accompanying drawings, forming 25 part of this specification, Figure 1 is a perspective view of a car-coupling constructed in accordance with my invention. Fig. 2 is a vertical sectional view.

A refers to the car-body, to which the draw-head B is secured in the usual manner, so as 30 to be capable of a rearward spring movement. The draw-head B has the usual link-opening b, the rear portion of which is formed to provide a shoulder c, against which the swinging 35 coupling-pin C will abut when the link is in contact with the rear portion thereof. The part of the coupling-pin C which lies within the draw-head is rearwardly extended, and the lower portion thereof lies in a slot or re- 40 cess d, above which is the aperture within which the ordinary link lies to abut against the enlarged part of the coupling-pin. The swell or enlargement of the depending portion of the coupling-pin will vary according 45 to the different lengths of links and the amount of play it is desired to give between the cars. The coupling-pin C has formed integral therewith a rearwardly-extending portion C', the end of which is bent downward 50 for a short distance, as shown in Fig. 2, and this coupling-pin is secured to the draw-head by a horizontal pin e, which passes through

the lugs or ears f f on the upper side of the draw-head, the pin being secured in place by a spring-key, so that it can be readily removed when desired. In front of the horizontal perforations in the draw-head through which passes the pin e is an opening or aperture E, into which may be passed an ordinary coupling-pin when the coupling-pin C is removed, and rear of the lugs f f the upper face of the draw-head is recessed at F, over which will lie the member C' of the coupling-pin, and within this recess F normally lies the lower end of a bell-crank lever G, which is pivoted to the car-body, the forward end thereof being bent at right angles to engage with the member C of a coupling-pin. This bell-crank lever is either operated from the sides of the car by a rod H, having a central bent portion which engages with one member thereof, or by a flexible connection I and rod I', which extends to the top of the car.

A car-coupling constructed as shown in the drawings will be automatic on operation, and 75 is adapted to be used with the ordinary coupling-links, and should for any reason it be desired to do away with the automatic feature of my invention the pivoted coupling-pin C can be removed and the ordinary coupling-pin used in connection with the draw-head.

Draw-heads of ordinary construction can be readily changed to adapt my improvements thereto.

85 The rear swell on the lower member of the coupling-pin not only gives greater width and strength to said pin, but locates one end of the coupling-link well within the draw-head, so that the draw-heads when coupled will be held close.

Having thus described my invention, what I claim as new, and desire to secure by Letters Patent, is—

In a car-coupling, the combination of the 95 draw-head B, having a link-opening and a central narrow recess or slot which extends below the link-opening to form a shoulder c, a swinging coupling-pin C, having the lower rear portion thereof enlarged, the member C' 100 of said coupling-pin extending rearwardly and provided with a bent end, as shown, in combination with an uncoupling-lever G, pivoted above the draw-head, the forward lower

end of the same being bent at right angles to engage with the member C' of the coupling-pin, a crank-shaft II, adapted to engage with the upper member of the bell-crank lever, and 5 connections I and I', connected directly to said uncoupling-lever, substantially as shown, and for the purpose set forth.

In testimony whereof I affix my signature in presence of two witnesses.

CHARLES N. ALDERMAN.
